ALVA L. GOODKNIGHT, OF HEAVENER, OKLAHOMA.

AIR-BRAKE MECHANISM.

1,322,783.

Specification of Letters Patent. Patented Nov. 25, 1919.

Application filed September 14, 1918. Serial No. 254,120.

To all whom it may concern:

Be it known that I, ALVA L. GOODKNIGHT, a citizen of the United States, residing at Heavener, in the county of LeFlore and State of Oklahoma, have invented a new and useful Improvement in Air-Brake Mechanism, of which the following is a specification.

My invention relates to air-brake mechanism of the class and type patented to me, on October 3, 1905, No. 800,736, and on February 20, 1906, No. 813,090, and generally to the standard triple valve air-brake mechanism.

The object of my invention is to improve and simplify the construction of the triple valve air-brake mechanism by first, the provision of a non return check valve which is adapted for easy application to standard air-brake mechanism, as for instance, the Westinghouse type, and second, by the provision of an air duct which communicates with the auxiliary chamber, forwardly and rearwardly of the triple valve piston, and directly controlled by the non return check valve, whereby, in a service application, a direct communication is automatically established between the train pipe and auxiliary reservoir, and in a full service application or service applications the brake cylinder pressure may be raised to any desired train pipe pressure and, thereby, obtain the advantage of straight air system, and also, to allow recharging of the auxiliary reservoir and brake cylinder, after either graduated or emergency reduction and retain the brake cylinder pressure, thereby, obviating the necessity for moving the brake to retard or full release to re-charge.

I attain these objects and other advantages by means of the mechanism illustrated in the accompanying drawing in which the figure, is a sectional view of a standard air-brake mechanism to which my invention is operatively applied, and showing the air duct under control of the non return check valve.

Similar numerals of reference refer to corresponding parts through the view.

The numeral 1, indicates a standard type of triple valve air-brake mechanism and which embodies my invention. My invention consists of a non return check valve structure 2, comprising a case 3, a valve seat 4, formed at the inner end of the case, a valve 5, having a stem 6, provided with a

compression spring 7, and a passage 8, in the lower side of the case, and which communicates with an air duct 9, which terminates forwardly and rearwardly of the triple valve piston 10, in the auxiliary chamber 11. The duct 9, is opened through the gasket 12, and enters the metal case 13, of the mechanism, extending a little distance inwardly, and then turns upwardly and outwardly to the valve 5, which normally obstructs the passage of air through the duct 9. A duct 14, is opened in the wall of the auxiliary chamber 11, and communicates with opening 8, in the case 3, and is adapted to communicate with the duct 9, through the valve seat 4, when the valve 5, is withdrawn from the seat. The forward terminal of the duct 9, is located at a point immediately below the wall of the auxiliary chamber 11, so that the upper margin of the piston 10, when in emergency position, shall obstruct the entrance to the duct and prevent air from the train pipe 15, passing therein. The other terminal of the duct 14, is located and positioned at the outer end of the feed groove 16, in the wall of the auxiliary chamber 11. The valve case 3, is provided with external screw threads on its inner end, which are adapted to be received by internal screw threads provided in the case of the brake mechanism. An annular bead or flange 17, is formed on the exterior of the case 3, at a point thereon adapted to limit the adjustment of the same to a proper adjustment of the valve seat 4, to the gasket 12.

My invention constructed as I have above described, operates as follows:

With the brake valve in running position, and the feed valve adjusted to 70 pounds, train pipe pressure, and main drum pressure at 90 pounds, air flows back until all auxiliary reservoirs of the brakes on the cars throughout the train are equalized at 70 pounds with that of the train pipe pressure. When descending grades and it is necessary to re-charge the auxiliary reservoirs without releasing the brakes, the usual service application is made and, while the valve is in lap position, the feed valve adjustment is changed down to almost the reduced pressure in the auxiliary reservoirs. Then the brake valve handle is placed in running position and the air flows back and, as the triple slide valve has a normal resistance of about three pounds, train pipe air cannot

force it to release and thus it remains in lap position. The train pipe air enters the port 18, and passes through the duct 9, to the valve 5, which lifts against the weak tension of the spring 7, off of its seat, the air flowing into and through the duct 14, and out of port 19, into the auxiliary reservoir 20, as shown by the arrows in the drawing, and thus keeping it re-charged up to 10 train pipe pressure. When re-charged, the valve 5, is forced to its seat by its spring and air pressure. Should it become necessary to apply the brake with a heavier application, the train pipe air is again reduced, 15 in the usual manner and, as valve 5, is seated, the auxiliary air cannot flow back through it, therefore, the greater pressure in the auxiliary reservoir forces the piston 10, to the left against the stem 21, and compression spring 22, until the piston is seated against the gasket 12, thereby closing port 18, and at the same time, the slide valve 23, has moved by and opened port 24, which leads to brake cylinder port 25, thus 20 allowing auxiliary and brake cylinder pressure to equalize. In this position, should it be necessary to re-charge, the feed valve is adjusted down to almost equal with the auxiliary pressure, when the brake valve is 25 placed again in running position, train pipe air then flows back up against piston 10, which is then seated against the gasket 12 and, with the assistance of the spring 22, and stem 21, forces the piston 10, to the 30 right, when the annular flange 26, engages the slide valve 23, and forcing the valve to the right until the annular flange 27, on stem 21, is seated against the wall 28. As the slide valve 23, does not move far enough 35 to the right to close port 24, in this operation, the piston 10, has uncovered or opened the port 18, thereby permitting train pipe air to flow through the port mentioned and into the duct 9, and, lifting the valve 5, off 40 of its seat, flowing into duct 14, and through feed port 19, into the auxiliary reservoir through auxiliary chamber 11, and, as the port 24, is open, flows through this port into the brake cylinder, keeping the auxiliary 45 reservoir and brake cylinder recharged, thus securing a straight air feature. In this way the auxiliary and brake cylinder pressure may be increased, by slowly adjusting train pipe pressure up with the feed valve until 50 the maximum braking power is obtained. When it is desired to release the brakes, it is accomplished in the usual manner, by placing the brake valve in full release position, permitting the main reservoir air pressure, in large volume, to flow back through the train pipe to force the piston 10, to assume full release position and passing through feed port 19, in the outer end of the feed groove 16, and opening the latter, thus 55 permitting the auxiliary reservoir to re-

charge in the usual manner through the feed groove and which is the same size as the feed port 19. The valve 5, and the feed port 19, have no function to perform after the brake moves to release position, being 70 functionally limited to recharging the brake while it is set.

In the drawing I have shown the position of the triple valve piston 10, in a service application of the brake, by dotted lines 29, 75 and its position in a release application, by dotted lines 30, and the corresponding rearward position of the valve 23, in the applications mentioned, by dotted lines 31 and 32, respectively. 80

Having fully described my invention and explained the manner of its operation what I claim is—

1. In an air brake mechanism having a brake cylinder an auxiliary reservoir and a triple valve influenced by train pipe air pressure and auxiliary reservoir air pressure, the combination with the triple valve, of an air duct having an inlet port in the gasket seat of the triple valve piston constantly presented to train pipe air and an outlet port in the outward end of the feed groove in the cylinder and normally presented to auxiliary reservoir air, and a non return check valve operating in said air duct and adapted for normally closing the duct to auxiliary reservoir air and yielding to permit train pipe air to flow through the duct and recharge the auxiliary reservoir. 90

2. In an air brake mechanism having a brake cylinder an auxiliary reservoir and a triple valve influenced by train pipe air pressure and auxiliary reservoir air pressure, the combination with the triple valve, of an air duct having an inlet port opening in the gasket seat of the triple valve piston and constantly presented to train pipe air and adapted to be closed by the triple valve piston when the latter is seated on its gasket seat and an outlet port opening in the outward end of the feed groove in the cylinder and normally presented to auxiliary reservoir air, and a non return check valve operating in said air duct and adapted for normally closing the duct to auxiliary reservoir air and yielding to permit train pipe air to flow through the duct and recharge the auxiliary reservoir. 110

3. In an air brake mechanism having an auxiliary reservoir, a brake cylinder and a triple valve influenced by train pipe air pressure and auxiliary reservoir air pressure, the combination with the triple valve, of an air duct having an inlet port opening in the gasket seat of the triple valve piston and constantly presented to train pipe air and adapted to be closed by the triple valve piston when the latter is seated on its gasket seat and an outlet port opening in the 125

outward end of the feed groove in the cylinder and normally presented to auxiliary reservoir air, and a non return check valve operating in said air duct and adapted for 5 normally closing the duct to auxiliary reservoir air and yielding to permit train pipe air to flow through the duct and recharge the auxiliary reservoir after a service application of the air brake.

10 4. In an air brake mechanism having an auxiliary reservoir a brake cylinder and a triple valve influenced by train pipe air pressure and auxiliary reservoir air pressure, the combination with the triple valve, of an 15 air duct having an inlet port opening in the gasket seat of the triple valve piston and constantly presented to train pipe air and adapted to be closed by the triple valve piston when the latter is seated on its gas- 20 ket seat and an outlet port opening in the outward end of the feed groove in the cylinder and normally presented to auxiliary reservoir air, and a non return check valve operating in said air duct and adapted for 25 normally closing the duct to auxiliary reservoir air and yielding to permit train pipe air to flow through the duct and recharge the auxiliary reservoir after a full service

or an emergency application of the air brake.

5. In an air brake mechanism having an auxiliary reservoir a brake cylinder and a triple valve influenced by train pipe air pressure and auxiliary reservoir air pressure, the combination with the triple valve, 30 of an air duct having an inlet port opening in the gasket seat of the triple valve piston and constantly presented to train pipe air and adapted to be closed by the triple valve piston when the latter is seated on 35 its gasket seat and an outlet port opening in the outward end of the feed groove in the cylinder and normally presented to auxiliary reservoir air, and a non return check valve operating in said duct and adapted 40 for normally closing the duct to auxiliary reservoir air and yielding to permit train pipe air to flow through the duct and recharge the auxiliary reservoir and the brake cylinder after a full service or an emergency application of the air brake.
